MAGNETIC SHIELD FOR ELECTRICAL APPARATUS

Louis E. Sauer, Sharon, Pa., assignor to Westinghouse Electric & Manufacturing Company, East Pittsburgh, Pa., a corporation of Pennsylvania

Application April 11, 1941, Serial No. 388,070

5 Claims. (Cl. 175—361)

My invention relates to electrical apparatus, such as current-limiting reactors of the oil-immersed type, and particularly to means for shielding the casing or tank surrounding the reactor coils from the stray or leakage magnetic flux that might otherwise enter the wall of the casing structure.

If the casing for containing the reactor is of the usual steel construction, the hysteresis and eddy current and other stray losses in the casing wall may become very large due to the passage of the leakage magnetic flux along the wall of the casing, thus causing excessive heating and objectionable energy losses therein.

The above-mentioned difficulties may be overcome by providing a path of low magnetic reluctance in the region between the casing and the reactor winding for shunting the lines of magnetic flux away from the walls of the casing. Such magnetic shield structures have been used built in as part of the winding assembly and removable from the casing with the winding. Such construction is, however, satisfactory only with the smaller sizes of reactors and require extra heavy coil supporting parts. Magnetic shield structures separate from the reactor winding assemblies have also been used consisting of sheets of magnetic sheet material extending between upper and lower supporting rings comprising a structure separate from the winding assembly and separate from the tank or casing structure, and which assembly is positioned and supported in the casing structure separately from the winding assembly. Such magnetic shield structures are difficult to handle and to properly brace within the casing, and special precautions must be taken to provide insulated joints in the upper and lower supporting rings and to insulate them from the casing in order to avoid excessive losses.

In accordance with my invention, a plurality of individual bundles of punchings of ribbon-like strips of magnetic sheet steel plates is provided, and the strips of each bundle tacked together, for example, by running beads of welds across the back of the bundle, that is, on the side thereof to be mounted nearest to the tank or casing wall. The ends of the ribbon-like strips are then welded to steel terminal plates, which are in turn welded to the inner wall of the casing structure so as to mount the bundles of strips of magnetic material in spaced relation to the casing wall.

Each bundle of strips of magnetic material, together with the terminal plates at each end thereof, comprises a separate unit which is easy to handle, and after being welded to the tank wall becomes a part of the tank structure. By interleaving different lengths of punchings, it is possible to construct the shields so that the cross-

section is graded to the amount of flux to be carried by it so that the central portion lengthwise of the structure, which must carry the largest amount of flux, may have a greater effective cross-section of magnetic material than the end portions which are required to carry lesser amounts of flux. This provides for a more economical use of material than prior structures. This construction also is more economical in the use of the space within the casing wall, since only a slight spacing of the shield from the casing wall is necessary which is much less than that required where a separate structure removable from the casing is positioned between the casing and the windings. Because of the actual contact between the upper and lower ends of the shield unit structures with the wall of the casing, flux which enters the casing wall above and below the shield can enter and pass along the shield structure, instead of being forced to continue along the tank wall, thus resulting in lower losses.

One object of the invention is the provision of a magnetic shield for shielding the casing enclosing an oil-immersed reactor from the effects of leakage flux that is simple and economical to manufacture, efficient in operation, easy to handle, and that is strongly braced against shipping and short-circuiting forces.

Other objects and advantages of my invention will be apparent from the following description of a preferred embodiment, reference being had to the accompanying drawing in which:

Figure 1 is a top view of a casing structure, with the cover removed, showing the outline of a three-phase reactor positioned therein and showing the location of the bundles of steel plates arranged in accordance with the invention;

Fig. 2 is a vertical sectional view of a portion of the casing showing the location of a bundle of sheet steel strips comprising a shield unit structure and the location of the reactor winding, and indicating in dotted lines the general path of the lines of leakage magnetic flux;

Fig. 3 is a front elevational view of one of the individual unit structures comprising the shield; and

Fig. 4 is a rear elevational view of the same structure prior to its attachment to the casing wall.

In the drawing, a casing structure 1, having an upper outwardly extending flange 2 for supporting the cover, is shown containing windings 3 of a three-phase reactor structure. A plurality of shielding units 4 are shown separately attached to the inner wall of the casing and extending to an elevation above the top and below the bottom of the winding 3 in the region between the winding and the casing wall in

which the leakage magnetic flux is large. Referring particularly to Figs. 3 and 4, the bundle 5 of strips of magnetic sheet material may comprise certain strips that extend from the top 6 of the bundle to an elevation 1 near the lower end of the bundle of strips, and certain of the strips may extend from the bottom 8 of the bundle upwardly to an elevation 9. Between the top 6 of the bundle and the elevation 9, and also between the bottom 8 and the elevation 1, the number of strips will, therefore, be half of those between elevations 7 and 9 comprising the central portion of the unit. If desired, additional strips of magnetic material of shorter length may also be fitted between those shown to additionally widen the unit for a desired portion of its length.

A steel terminal plate 11 is provided adjacent the top of the bundle of strips and is welded thereto by running beads of weld 18 and 12, as shown in Fig. 3, and a similar lower terminal plate 13 is provided at the lower end of the bundle which is welded to the strips at 19 and 14. Running beads of weld may also be applied across the edges of the bundle of strips at spaced intervals, as shown at 15 in Figs. 4 and 2. Preferably, these beads of weld are positioned on the back of the bundle; that is, the side adjacent to the casing wall. The shield is made up of a plurality of the structural units of the character shown in Figs. 3 and 4 positioned about the inner wall of the casing, as shown in Fig. 1, and attached thereto by welds on the upper and lower edges of the terminal plates 11 and 13, as shown at 16 and 17 in Fig. 2. This type of shielding structure is very economical of shielding material, since it is possible to space the individual units in accordance with the amount of shielding needed, so that on parts of the casing wall where greater shielding is needed these units may be spaced closely together along the casing wall, while on parts of the wall where less shielding is needed they may be spaced further apart and still provide adequate shielding. Also, the amount of material in different structural units may be varied by using strips 5 having different widths, so that a larger cross-section of material may be provided by using wider ribbon strips where more shielding is desired. The number of strips used in a particular unit may also be varied, if desired, so that this type of construction is not only economical of the space required for it within the casing structure, but also makes the more efficient use of shielding material readily controllable.

It will be apparent to those skilled in the art that modifications of the structural details may be made within the spirit of the invention, and I do not wish to be limited otherwise than by the scope of the appended claims.

I claim as my invention:

1. In a current-limiting reactor, a reactor winding, a casing of magnetic material about the winding, a magnetic shield between the winding and the casing comprising a plurality of units separately attached to the casing and each comprising a plurality of strips of magnetic material attached together to form a compact bundle, and terminal plates attached to the sides of said bundle of strips and to the side wall of the casing for supporting the bundles in spaced relation from the casing wall, at least certain of said strips having a length less than the length of the bundle and so arranged in the bundle that the number of strips in the end

portions of the bundle is less than the number comprising the central portion thereof.

2. In a current-limiting reactor, a reactor winding, a casing of magnetic material about the winding, a magnetic shield between the winding and the casing comprising a plurality of units separately attached to the casing and each comprising a plurality of strips of magnetic material attached together to form a compact bundle and terminal plates welded to the sides of said bundle of strips adjacent their ends, said terminal plates being welded to said casing wall to support the bundles of strips in spaced relation from the casing wall and from each other.

3. In a current-limiting reactor, a casing of magnetic material, a reactor assembly therein including an electrical winding having its axis positioned vertically within the casing, a magnetic shield between the winding and the casing comprising a plurality of units each comprising a plurality of strips of magnetic material attached together at intervals by beads of welds across the back of the strips, said units being positioned vertically within the casing and attached to the inner side wall of the casing in spaced relation therefrom, said strips having a length less than the length of the bundle and so arranged in the bundle that certain strips extend from one end of the bundle to a location spaced from the other end and the remaining strips extend from the other end to a location remote from the first providing overlap of the strips in the central portion of the bundle.

4. In a current-limiting reactor, a casing of magnetic material, a reactor assembly therein including an electrical winding having its axis positioned vertically within the casing, a magnetic shield between the winding and the casing comprising a plurality of units each comprising a plurality of strips of magnetic material attached together at intervals by beads of welds across the back of the strips, said units being positioned vertically within the casing, and terminal plates of magnetic material attached to the ends of said units and to the inner side wall of the casing to support the strips of magnetic material in spaced relation from the casing wall to provide a continuous magnetic path through the strips from the upper side wall to the lower side wall.

5. In a current-limiting reactor, a casing of magnetic material, a reactor assembly therein including an electrical winding having its axis positioned vertically within the casing, a magnetic shield between the winding and the casing comprising a plurality of units each comprising a plurality of strips of magnetic material attached together at intervals by beads of welds across the back of the strips, said units being positioned vertically within the casing, and terminal plates of magnetic material attached to the ends of said units and to the inner side wall of the casing to support the strips of magnetic material in spaced relation from the casing wall to provide a continuous magnetic path through the strips from the upper side wall to the lower side wall, at least some of said strips of magnetic material having a length less than that of the group of strips so that a lesser than the whole number of said strips are attached to the terminal plates, thus providing a greater cross-section of active magnetic material in the central portion of the unit than adjacent the ends.
